[57] CLAIM

I claim the ornamental design for a multifunction landscape rake head, as shown.

DESCRIPTION

FIG. 1 of the drawings is a perspective view showing the front, top, and right side of a multifunction landscape rake head embodying the design of my invention;

FIG. 2 is a front view;

FIG. 3 is a right side view;

FIG. 4 is a left side view;

FIG. 5 is a back view; and,

FIG. 6 is a bottom view.
